UNITED STATES PATENT OFFICE.

THOMAS MIDGLEY, JR., OF DAYTON, OHIO, ASSIGNOR TO THE DAYTON ENGINEERING LABORATORIES COMPANY, A CORPORATION OF OHIO.

MERCURY-COOLING SYSTEM.

1,328,051.

Specification of Letters Patent. Patented Jan. 13, 1920.

Application filed January 12, 1918. Serial No. 211,694.

To all whom it may concern:

Be it known that I, THOMAS MIDGLEY, Jr., a citizen of the United States of America, residing at Dayton, county of Montgomery, 5 and State of Ohio, have invented certain new and useful Improvements in Mercury-Cooling Systems, of which the following is a full, clear, and exact description.

This invention relates to self contained 10 cooling systems for spark plugs and puppet valves, and machine parts of a similar character of which a portion thereof is subjected to a high degree of temperature.

The object of this invention is the 15 provision of means for preventing the clogging of the cooling medium contained in the cooling system, and particularly where the passages in the system for the cooling medium are small.

Further objects and advantages of the 20 present invention will be apparent from the following description, reference being had to the accompanying drawings, wherein preferred embodiments of the present invention 25 are clearly shown.

In the drawings:

Figure 1 is a longitudinal sectional view 20 of a spark plug embodying the present invention;

Fig. 2 is a bottom plan view thereof; and Fig. 3 is a longitudinal section view of a 30 valve showing the application of the present invention.

Referring to the drawing, 20 designates 35 the spark plug having a shell portion 21 carrying shell points 22. 27 designates the center electrode carrying a center point 28, and supported by the shell 21 by means of bushing 37, packing glands 32 and 34, and 40 insulating members 30, 36 and 31. Radiator nut 41 and washer 39 serve to retain the center electrode in position longitudinally 45 of the spark plug. 42 designates the terminal binding nut. The center electrode 27 is provided with a chamber 52 having a heat 50 transferring lining 43 of metallic amalgam. 47 designates a quantity of mercury at the bottom of this chamber 52.

The operation of the cooling system is as 55 follows:

When the center contact is heated by the 60 burning gases in the engine cylinder, the heat therefrom passes from the head portion of the center electrode 27 into the quan-

65 tity of mercury 47, which is caused to boil 55 and evaporate and ascend in a vaporous state to the upper end of the chamber. The heat from the mercury vapor will be transferred into the wall of the electrode through the heat transferring amalgam lining 43. 60 From the wall of the electrode heat will be radiated by means of the radiator nut 41. The mercury vapor being cooled upon giving up its heat in the manner described, will condense and return to the bottom of the 65 tube; again to receive heat from the center contact and to conduct the same away to the upper end of the tube.

The spark plug thus far described is not 70 my invention but is described and claimed in the copending application of Charles F. Kettering, Serial No. 211,425, filed January 11, 1919.

In spark plugs, of the sizes used generally 75 in automobile engine work, the diameter of the chamber in the center electrode is necessarily small. I have discovered in the operation of such spark plugs that instead of the mercury vapor, upon condensing, running down the side of the chamber to the bottom, as in the case of chambers of large diameter, there is a tendency for the mercury, upon condensing, to be held in the upper end of the chamber by the pressure 80 of the vapor underneath. The broken line 85 47^a in Fig. 1 indicates the position taken by the mercury on condensing in cooling chambers of small diameter. My invention resides in the provision of devices which 90 will overcome the difficulty just described. I have discovered that by providing some means which will permit the passage of the uncondensed mercury vapor through the clogging body of mercury, and which will not interfere with the operation of the cooling 95 system, that I can utilize the pressure of the mercury vapor to force the clogging mercury down to the bottom of the cooling chamber. As a practical embodiment of my discovery, I have provided in the chamber 52 of the center electrode 27 a vent member 50 consisting of a bundle of small wires loosely twisted together located centrally of, and extending throughout the length of said cooling chamber. It has been 100 found that the mercury will not collect in the interstices between the wire strands of the member 50, and therefore the vapor un-

105

derneath the clogging body of mercury at 47^a, has a free passage upwardly through the member 50, whence said vapor may find its way to a point above the mercury and can force the same downwardly to the bottom of the chamber.

Referring to Fig. 3, 53 designates a valve having a head 48 to which is joined as by welding at X, a valve stem 51 having a head 10 portion 23 which is provided with heat radiating fins 49. As in the case of the center electrode 27 of the spark plug just described, the valve stem 51 is provided with a cooling chamber 52 having a chamber lining 43 of 15 metallic amalgam. 47 designates a quantity of mercury at the bottom of the chamber 52 and the function of said mercury is exactly the same as in the case of mercury 47 contained in the cooling chamber of the spark 20 plug. 47^a designates the position taken by the mercury upon condensing in valve cooling chambers of small diameters.

Valves of the kind illustrated in Fig. 3 are described more fully and claimed in the co-pending application of Charles F. Kettering, Serial No. 211,156, filed January 10, 1918 and in my copending application Serial No. 211,224, filed January 10, 1918. Fig. 3 shows, however, an application of my invention to a valve having a cooling chamber of small diameter. 50 designates the vent member having the same function as the member 50 of the spark plug.

While I have shown the improved cooling system embodying my invention, as applied to a spark plug and an engine valve, I wish to have it understood that the application of my invention is not to be limited to the structures described, but that said invention may be applied generally to other mechanical parts of a similar character having a self contained cooling system, such other applications of my invention all coming within a scope of the claims which follow.

What is claimed is as follows.

1. In a device of the character described, the combination with an element to be cooled provided with a cooling chamber; of a fluid cooling medium in the chamber; and means located in the chamber providing for the passage of the fluid cooling medium throughout the entire length of the chamber.

2. In a device of the character described, the combination with an element to be cooled provided with a cooling chamber; of

a fluid cooling medium and vent member located in the chamber.

3. In a device of the character described, the combination with an element to be cooled 60 provided with a cooling chamber; of a quantity of fluid metal and vent member located in the chamber.

4. In a device of the character described the combination with an element to be cooled 65 provided with a cooling chamber; of a heat transferring lining for the chamber; a fluid cooling medium in the chamber; and a vent 70 member located in the chamber.

5. In a device of the character described, the combination with an element to be cooled provided with a cooling chamber; of a heat transferring lining for the chamber; a fluid 75 cooling medium in the chamber; and a vent member located in the chamber.

6. In a device of the character described, the combination with an element to be cooled provided with a cooling chamber; of a heat transferring lining for the chamber; a fluid 80 cooling medium in the chamber; and a vent member located in the chamber.

7. In a device of the character described, the combination with an element to be cooled provided with a cooling chamber; of a heat 85 transferring amalgam lining for the chamber; a quantity of mercury in the chamber, and a vent member located in the chamber.

8. In a device of the character described, the combination with an element to be cooled 90 provided with a cooling chamber; of a heat transferring amalgam lining for the chamber; a quantity of mercury in the chamber, and a vent member located in the chamber, said vent member comprising a bundle of 95 wires loosely twisted together.

9. In a spark plug, the combination with a spark plug shell; of a center electrode separated by said shell but insulated therefrom, said electrode including a hollow stem portion and a head portion carrying an electrode spark point, said hollow stem portion adapted to contain a quantity of fluid cooling medium; and means for closing the upper end of said stem portion and for supporting a vent member extending down to the bottom of said stem portion.

In testimony whereof I affix my signature.

THOMAS MIDGLEY, JR.
